UNITED STATES PATENT OFFICE.

MAURICE B. SHWAYDER, OF DENVER, COLORADO.

DESIGN FOR AN ATTACHING PLATE FOR SUITCASES OR SIMILAR ARTICLES.

Application filed May 27, 1921. Serial No. 473,151. Term of patent 7 years.

To all whom it may concern:

Be it known that I, MAURICE B. SHWAYDER, a citizen of the United States, residing at 1553 Platte Street, in the city and county of Denver, and State of Colorado, have invented a new, original, and ornamental Design for an Attaching Plate for Suitcases or Similar Articles, of which the following is a specification, reference being had to the accompanying drawing, forming part thereof.

a suitcase the parts of which adjacent the loops, have been shown in broken lines;

What I claim is:

The ornamental design of an attaching plate for suitcases or similar articles as shown.

MAURICE B. SHWAYDER.
